COMBINED CARVING BOARD AND JUICE
RECEIVER

Siegmund Zekowski, Far Rockaway, N. Y.

Application December 2, 1949, Serial No. 6,373

Term of patent 14 years

(Cl. D44—3)

To all whom it may concern:

Be it known that I, Siegmund Zekowski, a citizen of the United States, resident of Far Rockaway, in the county of Queens, State of New York, have invented a new, original, and ornamental Design for a Combined Carving Board and Juice Receiver, of which the following is a specification, reference being had to the accompanying drawing, forming part hereof.

In the drawing,

tially like Figure 1, but showing the pan partly withdrawn.

I claim:

The ornamental design for a combined carving board and juice receiver, substantially as shown.

SIEGMUND ZEKOWSKI.
